[57] CLAIM

The ornamental design for an insulated cover for a
faucet or the like, substantially as shown and described.

DESCRIPTION

FIG. 1 is a side elevational view of an insulated cover
for a faucet or the like showing my new design, the
other sides being the same as the side shown;
FIG. 2 is a front elevational view thereof; and
FIG. 3 is a rear elevational view thereof.

FIG. 1.

FIG. 2.

FIG. 3.
